UNITED STATES PATENT OFFICE.

EARL P. WETMORE, OF CONCORD, MICHIGAN, ASSIGNOR TO THE ANOILCOAL BURNER CO., OF TOLEDO, OHIO, A CORPORATION OF DELAWARE.

METHOD AND APPARATUS FOR BURNING FUEL.

Application filed October 23, 1924, Serial No. 745,312. Renewed March 17, 1928.

This invention relates to a fuel burner, and, more particularly, to a burner adapted to produce a readily combustible suspension in air of fuels of a semi-solid nature, such as the 5 stiff pastes formed of solid and liquid fuels, or of other plastic fuels of similar nature.

Composite fuels of the type indicated are commonly formed of the minute particles of powdered fuel, from which the ash content 10 may have been removed in whole or in part, and of a liquid fuel which surrounds the particles with a film or layer of oil and serves to unite them into a coherent paste of a nature intermediate that of the solid and liquid fuels 15 of which it is composed and having characteristics different from those of either of their constituents, being usually of sufficient stiffness that it does not flow readily, and may be burned on a suitable grate in the manner of 20 solid fuels. Because of the greater flexibility in controlling combustion and in the consumption of the fuels, when fuels are burned in flames in the manner of fluid fuels, and the resulting greater efficiencies and economies in 25 combustion, it is however highly desirable to burn such fuels by atomizing and diffusing them in a current of air, so that they may be quickly ignited and burned, and then projecting the mixture of commingled air and 30 fuel into a combustion chamber in which its combustion may be completed. Owing to the physical characteristics of the composite fuels of the above mentioned types, in which the separate particles of solid fuel are tenaciously held together by their enveloping 35 films of oil, they can not be handled in the same manner as liquid fuels, which flow readily and are easily broken up to a mist, nor in the manner of pulverized fuels, which 40 are already in a fine state of division and partly mixed with air.

An object of my present invention is to provide a method and apparatus by which fuels of the above mentioned types and characteristics 45 may be divided and suspended in a current of air and enabled to be burned in the manner of fluid fuels.

Another object of the invention is to provide an apparatus in which fuels of the above 50 indicated types may be finely divided and suspended in a current of air in a condition to be readily burned and the quantity of air automatically controlled and regulated in accordance with the requirements of the fuel.

55 A further object of the invention is to pro-

vide an apparatus in which the fuel paste is positively and mechanically separated into finely divided particles and efficiently dispersed into a gaseous medium.

A still further object of the invention is to 60 provide an apparatus by which composite fuels of the above mentioned types may be fed at a uniform and readily controlled rate and dispersed into air in a state of division to be readily ignited and burned.

With these and other objects in view, which 65 will appear from the following detailed description of the invention, the invention comprises the method and apparatus described and set forth in the following specification 70 and claims.

The various features of the invention are illustrated in the accompanying drawings, in 75 which:

Figure 1 is a plan view, partly in section, of 75 a fuel burning apparatus embodying a preferred form of my invention,

Figure 2 is a longitudinal, elevational sectional view of the burner apparatus taken on 80 line 2—2 of Figure 1, and

Figure 3 is a front view of a fuel separating or disintegrating and dispersing device forming a part of the fuel burning apparatus.

In my present invention, a current or blast 85 of air is produced in a suitable conduit and delivered to a mixing chamber into which a supply of fuel is fed and divided and dispersed in the air, and from which it passes with the suspended fuel into a suitable combustion chamber. A supply of fuel paste is forced under a substantially uniform pressure 90 into an annular chamber encircling the air conduit, from which it passes through an annular opening or other suitable openings into the mixing chamber. The converging, inner, annular edge or edges of this

fuel paste is continuously sheared off in thin 95 particles and carried into the blast or current of air by means of cutting or shearing 100 blades which are preferably rotated at the inner edge of the fuel and as the fuel is forced into contact with them, serve to separate the fuel into fine particles or into the particles of solid fuel of which the paste is 105 formed. The cutting blades also serve to thoroughly mix and suspend the fuel in the blast of air. The rate of supply of the fuel is controlled as by controlling the width of the orifice or opening through which it is forced 110

in the air blast and the velocity of the air blast is automatically regulated in accordance with the feeding of the fuel as by a means through which the speed of the driving fan or other blast generating means is controlled.

Referring more particularly to the accompanying drawings, a blast of air is driven forwardly through a cylindrical conduit 10 by means of a fan 11, connected to a driving motor 12 or other driving means by means of a flange coupling 13. The air driven forwardly by the fan 11 passes through a narrowed or converging front end opening 14 of the conduit 10 into a mixing chamber 15 in which it receives a supply of fuel in finely divided form and carries this fuel suspended in a fine state of division into a combustion chamber or nozzle 16 in which it may be ignited and directed to a suitable furnace or other apparatus.

A supply of fuel to be fed into and divided and dispersed in the air blast, is charged into a hopper 17, to the rear of the conduit 10, and sinks downwardly into a conveyor tube 18, on the rear portion of which the hopper is mounted. The rear end of the tube 18 is closed by means of a plate 19 bolted to the end of the tube, and the front end curves upwardly at 20 and merges and leads into an annular chamber 21, encircling the front converging end 14 of the conduit 10. The fuel received in the tube 18 is forced forwardly in the tube and into the chamber 21 by means of a conveyor screw 22 supported on a shaft 23, the front end of which is journalled in a bearing 24 in the upwardly curving portion 20 of the tube and the rear end of which extends rearwardly through a bearing 25 in the plate 19 and is driven by means of a worm 26 and gear 27 mounted on the projecting rear end of the shaft. Sufficient clearance is provided between the screw 22 and the inner surface of the tube 18 so that the fuel is delivered to the annular chamber 21 under a substantially uniform pressure, any greater pressure being relieved by the slip between the screw and tube.

From the chamber 21 an annular sheet of fuel is forced forwardly and inwardly through an annular opening 28 formed between an annular edge 29 at the juncture of the surfaces of the mixing chamber 15 and the chamber 21, and a tapered outer surface 30 of the front end of the conduit cylinder 10. As the annular layer of fuel is pressed through the opening 28, thin strips or particles are sheared from its advancing front edge and thrown into the forwardly moving blast of air by means of a number of rotating blades 31, four blades being shown by way of example. The front faces 32 of the blades 31 are at an angle to the direction of movement of the fuel so that the fuel slices or particles are cut from the body of

the fuel and thrown forwardly to free the blades.

The blades 31 are preferably mounted on a central hub 33 having its rear face 34 curved outwardly to direct the air from the conduit 10 towards the outer portion of the mixing chamber 15 into intimate contact with the coal particles and insuring the distribution of the coal particles throughout the volume of the air. The air thus passes forwardly along the flaring face 34 and between the blades 31 and thus into intimate contact with the fuel being sheared or cut from the advancing sheet. The hub 33 is preferably mounted on a shaft 35 which extends from the fan 11 and is journalled in a bearing 36 supported centrally within the conduit cylinder 10 by means of three radial spiders 37 and is thus driven at the same speed as the fan.

As the pressure of the fuel within the chamber 21 is substantially constant, the rate at which the fuel is supplied through the opening 28 to the mixing chamber 15 is governed by the width of the opening 28. The width of the opening 28 may be varied by moving the cylinder 10 forwardly or rearwardly to move the surface 30 towards or from the edge 29. For this purpose, the cylinder 10 is slidably mounted in a cylindrical wall 38 extending rearwardly from the rear edge of the annular chamber 21 and may be moved longitudinally therein by any suitable actuating means. This actuating means may, and preferably does, comprise a pinion 39 mounted in fixed position on the cylindrical wall 38 and meshing with rack teeth 40 cut into the upper surface of the cylinder 10. The pinion 39 may be rotated to shift the rack teeth 40 and cylinder 10 by means of an actuating handle 41 or other means, which may be actuated by hand or by a pressure regulator or other automatic control means, to adjust the supply of fuel in accordance with the heat or energy demands of the burner.

For the most efficient and economical combustion, it is desirable to adjust the velocity or quantity of air supplied in the air blast in accordance with the fuel supply so that just sufficient air may be supplied to effect the complete combustion of the fuel. For this purpose, the speed of rotation of the motor 12 and accordingly of the fan 11 is controlled by means of a control rheostat 42, which is, in turn, controlled by the handle 41, or other means controlling the rotation of the pinion 39, so that, as the pinion 39 is rotated, the resistance in the rheostat 42 is varied and the velocity of the air blast proportioned to the width of the opening 28.

The apparatus may be built or constructed in any suitable manner or form. As indicated in the example shown in the accompanying drawings, the conveyor tube 18, annular chamber 21, mixing chamber 15, nozzle or

5 combustion chamber 16 and the rearwardly extending cylindrical wall 38 are preferably formed in a single, integral casting, properly machined to receive the cylinder 10 and to form the required opening edges, and the cylinder 10 is then mounted in and supported in the wall 38. The apparatus may be mounted on supporting feet or legs 43 on which the tube 18 rests. As indicated, the motor 12 and 10 fan 11 are most conveniently mounted within and movable with the cylinder 10.

15 As changes of construction could be made within the scope of the invention, it is desired that all matter contained in the above 15 description or shown in the accompanying drawings shall be interpreted as illustrative and not in a limiting sense.

Having described my invention, what I claim and desire to secure by Letters Patent is:

20 1. A method of burning plastic fuels which comprises feeding an annular sheet of plastic fuel inwardly and forwardly, shearing particles from the advancing edge of said sheet, 25 and passing a current of air within said sheet of fuel and deflecting it outwardly to the edge of fuel being sheared.

25 2. A method of burning plastic fuels which comprises feeding an annular sheet of plastic fuel inwardly and forwardly, controlling the rate of feeding of said fuel, shearing particles from the advancing edge of said sheet, passing a current of air within said sheet and deflecting it outwardly to the edge of fuel being sheared to pick up and disperse said particles, and controlling the rate of supply of air in accordance with the rate of feeding of fuel.

30 3. A method of burning plastic fuels which comprises feeding an annular sheet of plastic fuel inwardly and forwardly under substantially constant pressure, controlling the thickness of said sheet, shearing particles from the advancing edge of said sheet, passing a current of air within said sheet and deflecting it outwardly over the edge of said fuel being sheared to pick up and disperse said particles, and controlling the velocity of said air current in proportion to the thickness of said fuel sheet.

35 4. Apparatus for burning fuels of the type indicated which comprises, means for feeding fuel in an annular converging sheet, means for passing a current of air within said annular sheet, and means for shearing and dispersing particles from the advancing edge of said sheet into said current of air.

40 5. Apparatus for burning fuels of the type indicated which comprises, means for feeding fuel in an annular converging sheet, means for passing a current of air within said annular sheet and deflecting it outwardly over the advancing edge of said fuel sheet, and means for shearing and dispersing particles from said sheet into said current of air.

6. Apparatus for burning fuels of the type indicated which comprises means for feeding fuel in an annular converging sheet, means for controlling the rate of feeding of said fuel, means for passing a current of air within said annular sheet and deflecting it outwardly over the advancing edge of said sheet, means for controlling the quantity of air in said blast in proportion to the rate of feeding of said fuel, and means for shearing particles of fuel from said sheet into said air current.

7. Apparatus for burning fuels of the type indicated which comprises means for feeding fuel under substantially constant pressure in an annular converging sheet, means for controlling the thickness of said sheet, means for passing a current of air within and deflected outwardly over the advancing edge of said sheet, means for controlling the velocity of said air current in direct relation to the thickness of said fuel sheet, and means for detaching particles of fuel from the advancing edge of said sheet and dispersing them into said air current.

8. Apparatus for burning fuels which comprises an annular fuel feeding chamber, an annular opening extending inwardly and forwardly from said annular chamber, fuel cutting blades rotatable across the forward inner edge of said opening in the path of fuel therefrom, and means for blowing a current of air forwardly over the inner edge of said opening.

9. Apparatus for burning fuels which comprises an annular fuel feeding chamber, an annular opening extending inwardly and forwardly from said annular chamber, fuel cutting blades rotatable over the forward inner edge of said opening in the path of fuel therefrom, means for blowing air forwardly, centrally of said annular chamber, and means for deflecting said air outwardly to the edge of said opening.

10. Apparatus for burning fuels which comprises an annular fuel feeding chamber, an annular opening extending inwardly and forwardly from said annular chamber, means for controlling the rate of feeding of fuel through said opening, fuel cutting blades rotatable over the forward inner edge of said opening in the path of fuel therefrom, means for blowing air forwardly within the annular edge of said opening in the path of said blades, and means for automatically adjusting the velocity of said air current in relation to the rate of feeding of said fuel.

11. Apparatus for burning fuels which comprises an annular feeding chamber, an annular opening extending inwardly and forwardly from said annular chamber, means for supplying fuel to said feeding chamber under a substantially constant pressure, means for adjusting the dimensions of said annular opening, fuel cutting blades rotatable over the

forward inner edge of said opening in the path of fuel therefrom, means for blowing a current of air forwardly over the inner edge of said opening, and means for automatically adjusting the velocity of said current of air to correspond to the dimensions of said opening.

12. Apparatus for burning fuels which comprises an annular feeding chamber recess 10 having an annular inner edge and a mixing chamber forwardly thereof, and a rearwardly extending supporting cylinder, an inner cylinder within said supporting cylinder and slideable longitudinally therein and having an 15 inwardly tapering outer surface at its forward end in spaced relation to said annular edge and forming a feed orifice therewith, means for moving said inner cylinder longitudinally in said supporting cylinder to vary 20 the width of said annular orifice, means for forcing fuel to said annular chamber, and means for blowing air through said inner cylinder over the inner edge of said orifice.

13. Apparatus for burning fuels which 25 comprises an annular feeding chamber recess having an annular inner forward edge, and a mixing chamber forwardly thereof, and a rearwardly extending supporting cylinder, an inner cylinder slideable within said sup-

porting cylinder and having a tapered outer 30 edge in spaced relation to the edge of said chamber recess and forming a feed orifice therewith, means for sliding said inner cylinder to vary the width of said feed orifice, rotatable cutter blades rotatable over the inner edge of said orifice, means for forcing fuel to said annular chamber, means for blowing air through said inner cylinder over the edges of said orifice, and means for varying the 35 velocity of said air in relation to the width 40 of said annular fuel feed orifice.

14. Apparatus for burning fuels which comprises an annular fuel feed chamber having an inner forward edge, a cylinder slideable 45 to and from said edge and having a tapered outer edge surface in spaced relation to said forward edge to form an annular feed orifice of adjustable width, means for supplying fuel to said annular chamber under substantially constant pressure, cutter blades rotatable over the inner edge of said orifice, a fan and motor within said cylinder and driving said cutter blades, and means for controlling the speed of said motor and fan in definite 50 relation to the width of said fuel feed orifice. 55

In testimony whereof, I affix my signature.

EARL P. WETMORE
